UNITED STATES PATENT OFFICE.

JAMES HOWARD YOUNG, OF PITTSBURGH, AND WESLEY H. MILLER, OF WILKINSBURG, PENNSYLVANIA, ASSIGNEES TO H. H. ROBERTSON COMPANY, OF PITTSBURGH, PENNSYLVANIA, A CORPORATION OF PENNSYLVANIA.

GLAZING CONSTRUCTION.

Application filed September 24, 1924. Serial No. 739,643.

This invention relates to a glazing construction and has for its object to provide a simple, efficient, and inexpensive glazing construction, in which the supporting member, usually of steel, is protected against the corrosive action of water, and in which the glass panes or members are free or substantially free from internal strains and stresses whereby breakage of the glass panes or members is avoided or at least reduced to a minimum.

Provision is made for insulating the gutter member, usually of copper, from the steel supporting member, and for preventing contact of the glass members with the metal parts of the construction.

The supporting member has erected upon it a stud, extended through the insulating member for the gutter, the cushioning member for the glass members and the gutter member interposed between said insulating and cushioning members, and provision is made for causing the cushioning member to make a fluid tight joint about the said stud, whereby any moisture which may pass down on the outside of the said stud is prevented from entering the building and is caused to pass into the gutter. The stud member is preferably threaded and is engaged by a nut, which contacts with the cushioning member and when turned up compresses the latter and causes it to make a fluid tight joint with the stud.

The stud also serves to secure the cap member in position and the said cap member is constructed with a relatively narrow flange which cooperates with the glass members near the edges of the same, whereby a minimum area of a glass member is covered by the flange and a cushioning member interposed between said flange and glass member, so that the glass members at their edges may be heated indirectly by the sun's rays to such extent as to prevent or at least minimize internal stresses and strains and thereby avoid breaking of the glass members by uneven expansion of said glass members. Spacing members for the glass members are provided, which properly position the edges of the glass members with relation to the sides of the cap member.

These and other features of this invention will be pointed out in the claims at the end of this specification.

In the drawing illustrating the preferred embodiment of the invention, Fig. 1 is a plan of a sufficient portion of a glazing construction embodying the invention to enable it to be understood, and Fig. 2 a section on the line 2—2, Fig. 1.

Referring to the drawing, the improved glazing construction illustrated therein comprises glass members 10, 12, which are supported by a metal member 14, usually a steel angle bar secured to the roof or part of the building upon which the glazing construction is erected.

The supporting member 14 also supports a gutter member 13 preferably of copper and provided, as shown, with gutters 32 located on opposite sides of said supporting member. The gutter member 13 is insulated from the supporting member 14 by an insulating member 16, preferably a strip of felt saturated with asphalt, and the gutter member 13 supports a cushioning member 15 for the glass members 10, 12. The cushioning member 15 is preferably a strip of felt saturated with asphalt. The strips 15, 16, and the gutter member 13 are retained in place on the supporting member 14 by studs 24, only one of which is shown, which are erected upon the supporting member and distributed throughout the length of the latter. The studs 24 are preferably threaded and enter threaded openings in the flange 25 of the supporting member 14 and pass through suitable holes in the insulating member 16, gutter member 13, and cushioning member 15. The stud 24 above the cushioning member 15 is provided with a nut 28 and washer 30, which rest upon the cushioning member, and which compress the latter when the nut is set up, so as to form a fluid tight joint with the stud, and thereby prevent moisture which may pass down on the upper portion of the stud, from following the stud through the hole in the gutter into the building.

The stud 24 is extended up through a cap member 18, which covers the space between the glass members and rests on a cushioning member or strip 17 of waterproof material, preferably of felt saturated with asphalt, and which is interposed between the cap member 18 and the glass members 10, 12 and spans the space between the latter. The cap member 18 is provided with sub-

stantially narrow flanges 19, 20, and the glass members 10, 12, are arranged on the supporting member 14 so that only a relatively narrow width or area of the sides of the glass members are covered by the flanges of the cap member and the portion of the cushioning member 17, whereby a minimum amount or area of the glass members are not exposed to the sun's rays and, therefore, not directly heated thereby, but are indirectly heated to such extent as to avoid wide differences in temperature between the covered and uncovered portions of the glass and prevent, or at least reduce to a minimum, the formation of internal stresses in the glass with consequent breakage due thereto. This is especially true when the glass members 10, 12, are provided with a reinforcing wire mesh 34. The cap member 18 is pressed down on the glass members by a nut 26 or other suitable means, engaging the stud 24 above the cap member. The studs 24 have mounted upon them, washers or spacing members 27 of rubber or other resilient material which are of suitable size or diameter to properly space the glass members from each other and in proper relation to the sides of the cap member, so as to provide the glass members with the desired narrow or limited covered area at the sides thereof, and also to prevent the glass members striking the studs when the glass members are placed in position and especially when hurriedly slipped into position.

From the above description, it will be seen that any moisture which may leak into the space between the glass members, is taken care of by the gutters and conducted away, and is prevented from entering the building by following the studs 24. It will also be observed that the copper gutter member 13 is insulated and metallically disconnected from the steel supporting member 14 and corrosion of the steel member by electrolysis is prevented.

It will further be observed that internal stresses and strains at the edges of the glass are avoided. These highly desirable results are accomplished with a glazing construction, which is simple to manufacture and which can be installed at a minimum cost.

What we claim is:

1. In a glazing construction, in combination, a supporting member, a stud erected thereon, a gutter member fitted upon said stud, an insulating member interposed between said gutter member and said supporting member, a waterproof cushioning member upon said gutter member, glass members resting on said cushioning member and spaced apart, a cap member mounted on said stud, a cushion member between said cap member and said glass members and covering the space between the latter, means on

said stud for pressing said cap member toward said glass members, means on said stud cooperating with the cushioning member for the glass members to form a fluid tight joint with said stud, and a member on said stud in the space between said glass members to be engaged thereby for spacing said glass members. 65

2. In a glazing construction, in combination, a supporting member, a stud erected thereon, a gutter member fitted upon said stud, an insulating member interposed between said gutter member and said supporting member, a waterproof cushioning member upon said gutter member to electrically separate them, and means on said stud cooperating with said cushioning member to effect a fluid tight joint between said cushioning member and said stud. 75

3. In a glazing construction, in combination, a supporting member, a stud erected thereon, a gutter member fitted upon said stud member, an insulating member between said gutter member and said supporting member to electrically separate them, glass members, a cushioning member interposed between said glass members and said gutter member, and means on said stud for compressing said cushioning member to effect a liquid tight joint therewith. 85

4. In a glazing construction, in combination, a supporting member, a stud erected thereon, a gutter member supported by said supporting member, glass members located on opposite sides of said stud and spaced apart, a cushioning member between said glass members and said gutter member and spanning the space between said glass members, and means located between said glass member and cooperating with said cushioning member to effect a liquid tight joint between said cushioning member and said stud. 95

5. In a glazing construction, in combination, a rigid metal supporting member, a stud extended upwardly therefrom and in fixed relation thereto, a metal gutter fitted on said stud, an electrically insulating member fitted on said stud between said gutter and said supporting member, a cushioning strip mounted on said stud above said gutter, glass members resting on said cushioning strip on opposite sides of said stud and spaced therefrom, a cap member mounted on said stud, a cushioning strip mounted on said stud between the cap member and said glass members, and a yielding spacing member mounted on said stud between said glass members. 110

In testimony whereof, we have signed our names to this specification.

JAMES HOWARD YOUNG.
WESLEY H. MILLER.
